UNITED STATES PATENT OFFICE.

JAMES H. CASSON, OF DETROIT, MICHIGAN.

MOLDER'S TOOL.

No. 909,150.

Specification of Letters Patent.

Patented Jan. 12, 1909.

Application filed April 5, 1907. Serial No. 366,560.

To all whom it may concern:

Be it known that I, JAMES H. CASSON, a citizen of the United States of America, residing at Detroit, in the county of Wayne 5 and State of Michigan, have invented certain new and useful Improvements in Molders' Tools, of which the following is a specification, reference being had therein to the accompanying drawings.

10 This invention relates to an improved tool for molders' use in removing patterns from the sand and the object of the invention is to provide a suitable tool for the purpose which is simple, cheap and efficient in its operation 15 adapted for use in removing both wood and metal patterns.

It is also an object of the invention to provide such a tool with an operating handle which is so constructed as to adapt the device 20 to be used as a hammer for rapping the patterns to loosen the same in the sand, and to provide a device having the several advantages of the particular construction, arrangement and combination of parts, all as hereinafter more fully described reference being had to the accompanying drawings in 25 which—

Figure 1 is a side elevation of a device embodying the invention; Fig. 2 a similar view 30 of the modified form of spike, detached, and Fig. 3 a section through another modification.

As shown in the drawing, 1 is a cylindrical shaped member having a long tapering conical point 2, forming a spike the sharp pointed end of which is adapted to be driven a short distance into a wooden pattern which it is desired to remove from the sand in the process of forming a mold for casting a 40 metal article. Secured to the end of this spike in any suitable manner, as by a pin 3, is an externally screw-threaded stem 4 formed at its free end with a T-head or handle 5 of a size and shape to be conveniently grasped in the hand to lift the spike where the same has been driven into a pattern and also of a form and weight to adapt the tool to be used by the molder as a hammer for rapping the pattern to loosen it in 45 the sand.

To lift a metal pattern or one into which it is not desirable to drive the spike, spring fingers 6 adapted to be inserted in a hole in the pattern, are provided. These fingers extend 55 longitudinally of the spike and lie closely against the sides thereof, tapering

toward the point of the spike where each is provided with an outwardly projecting shoulder 7 forming a head. At their opposite ends the fingers are united by a block 8 having a screw-threaded opening to receive the screw stem 4 so that by turning said stem relatively to the fingers the spike is moved longitudinally, projecting the same outward between the fingers and forcing them apart or retracting the spike to lie wholly between the fingers. When the spike is so retracted, the free ends of the fingers lie closely together against the tapering point of the spike and may be inserted in a small hole in the pattern and the stem then turned to project the spike, the conical end of which acts as a wedge to force the fingers apart and bind the same in the hole in the pattern, the shoulders or head of the fingers 75 engaging the sides of the hole or when projected through the pattern they engage the underside thereof to prevent the fingers from slipping out when the operator lifts on the handle to withdraw the pattern from 80 the sand. When the handle is turned to move the spike inward between the fingers, said fingers by this spring action engage the side of the conical end of the spike closely and move toward each other, disengaging 85 their shoulders from the pattern and permitting the removal of the tool from the hole in the pattern.

When the spike is to be used to remove a wooden pattern from the sand, the handle 90 is turned to project the sharp point of the spike beyond the ends of the fingers and is then attached to the pattern to lift the same by driving this sharp point into the wood. It is evident however that the spring 95 finger may be omitted if so desired, and, when a hole is provided in the pattern, the spike may be driven into the hole, its tapered end wedging therein firmly enough to lift the pattern.

100 In Fig. 2 is shown a spike formed at its extreme point 9 with a wood-screw thread so that in removing wood patterns the point may be screwed into the pattern instead of being driven in, the spike being turned by 105 means of the handle and the fingers permitted to turn with the spike so that their position relative to the spike will not be changed by such turning.

When the tool is to be used exclusively 110 in handling large heavy metal patterns, the sharp point of the spike may be left off,

it being cut off midway between the base and the apex of the conical portion so that when the spike, which would then serve simply as a wedge to spread the fingers, is projected, the pointed end would not extend beyond the ends of the fingers and into the sand.

In Fig. 3, another modification is shown in which the spike is made in halves 11 secured together by a screw 12 and provided at its lower end with a socket 13 for the head of an ordinary wood screw 14 so that the screw can be renewed as it becomes worn thus not necessitating the purchase of an entire new spike.

Having thus fully described the invention what I claim is—

1. In a molder's tool, the combination of a cylindrical member having a conical end, 20 spring fingers adapted to engage the sides of the conical end and having shoulders at their lower ends, a block connecting said fingers at their upper end and having a

screw-threaded opening, a threaded stem on the cylindrical member engaging said opening and a T handle on the end of the stem.

2. In a molder's tool, the combination of a two-part member having a conical end and mating pockets therein adapted to receive a common screw, means for removably securing the two parts together, spring fingers connected at their upper ends adapted to engage the sides of the conical end and having shoulders at their lower ends, 35 a threaded stem on the two-part member engaging a threaded opening on the finger portion and adapted to move the parts in relation to each other and a handle on the stem.

In testimony whereof I affix my signature in presence of two witnesses.

JAMES H. CASSON.
